UNITED STATES PATENT OFFICE.

WALTER L. JOHNSTON AND FRED L. JOHNSTON, OF SIDNEY, NEBRASKA.

BEET-TOPPING MACHINE.

1,341,909.

Specification of Letters Patent.

Patented June 1, 1920.

Application filed July 12, 1916. Serial No. 108,863.

To all whom it may concern:

Be it known that we, WALTER L. JOHNSTON and FRED L. JOHNSTON, citizens of the United States, residing at Sidney, in the 5 county of Cheyenne, and State of Nebraska, have invented certain new and useful Improvements in Beet-Topping Machines, of which the following is a specification.

This invention relates to beet topping machines, and more particularly to a machine adapted to partially lift the beets from the ground and sever the crowns and leaves from the same.

One of the main objects of the invention 15 is to provide a machine of the character stated of simple construction and operation. A further object is to provide means for lifting the beets from the ground and topping them, and collecting the severed tops. 20 A still further object is to provide a beet harvesting machine in which the main frame of the machine is maintained in fixed relation to the ground surface over which the machine is drawn, beet holding and conveying means being rigidly secured to this 25 main frame so as to be closely adjacent to the ground surface and beet lifting means being provided in front of the holding and conveying means, this lifting means being 30 vertically adjustable whereby the height to which the beets are lifted may be quickly and easily varied to suit circumstances. A still further object is to provide topping means mounted above and closely adjacent 35 the beet holding and conveying means so that, by adjusting the lifting means so as to control the height to which the beets are lifted, the amount of crown or top of the beet which is severed from the body of the 40 beet may be accurately controlled. Further objects will appear from the detailed description.

In the drawings:—

Figure 1 is a side view of the machine, 45 Fig. 2 is a top plan view;

Fig. 3 is a front view of the main frame of the machine with certain parts of the driving mechanism omitted for clearness,

Fig. 4 is a plan view, partly in section, 50 of one of the beet holders.

Fig. 5 is a longitudinal central section of Fig. 4,

Fig. 6 is a plan view of one of the lower top holders,

55 Fig. 7 is a section on line 11—11 of Fig. 6,

Fig. 8 is a detail of the rack and quadrant for lifting the beet lifters, and

Fig. 9 is a detail of the lever for operating the shaft for adjusting the beet lifters.

The body of the machine is composed of 60 a main frame 1, and a tongue frame 2 pivotally connected to the front corners of the main frame and carrying the usual tongue 3, double-tree 4, and swingle-trees 5. The main frame 1 is provided with suitable cross braces 6 and 7 and longitudinal braces 8 and 9. An axle 10 is mounted in suitable brackets on the side bars 11 of the main frame, and has the ground wheels 12 keyed on its ends. Each ground wheel carries 70 a spur gear ring 13 which rings are in mesh with pinions 14 loose on the outer ends of the transverse counter shafts 15 and 15^a rotatably mounted in standards 16 secured on the side bars and longitudinal 75 brace bars of the main frame. Each pinion 14 is provided with an integral clutch element 17 adapted to coöperate with an element 18 feathered on the shaft in the usual manner. Normally, the clutch elements 18 80 are held outward in operative engagement with the clutch elements 17 of the pinions 14 by the action of coil springs 28 confined between the same and the outermost standards 16.

The shafts 15 and 15^a are each provided with a bevel gear 29 keyed thereon. This gear meshes with a bevel gear 30 keyed on the upper end of a shaft 31 rotatably supported in a suitable journal member secured 90 to the under faces of the brace bars 8 and 9. This shaft is composed of three sections connected by universal joints 32.

The lower section 31^a of shaft 31 carries a sprocket wheel 33 keyed thereon. This 95 wheel is mounted in a cylindrical recess 34 formed in one end of an elongated elliptical block 35 which is mounted in a rectangular casing 36, the inner side of which is open. The shaft 31^a projects slightly beyond the sprocket wheel 33 so as to form a bearing member which fits snugly into an aperture through the side wall of recess 34. A recess 34^a is provided at the other end of block 35 and a sprocket 33^a 105 similar to sprocket 33 is rotatably mounted therein on a screw bolt 37. The peripheral wall of block 35 is provided with a groove 38. A sprocket chain 39 is passed about the sprocket wheels 33 and 33^a and oper- 110

ates in the groove 38 of the block. This chain is provided with a series of equally spaced spurs 40. These spurs are shaped with a normal face and a beveled face and are so disposed on the chain 39 that, on the outer run of the chain, the normal faces of the spurs are directed rearward of the machine. The block 35 is provided, on its inner face, with two pairs of inwardly projecting lugs 41 at each end thereof. Cross pieces 42 are secured across these lugs and the ends of a comparatively strong bow spring 43 are secured to the pieces 42. This spring is secured at its center, to the back of casing 36 by means of rivets 44. The block 35 is provided on each side adjacent the recesses 34 and 34^a with a lug 45. This lug engages a similar lug 46 secured on the inner face of the side of casing 36 and serves to limit positively the outward movement of the block and the parts carried thereby. The casing 36 is provided in its upper side with a slot 47 which permits inward and outward movement of the shaft 31^a. By this means the block 35 and the bars carried thereby are resiliently mounted for limited inward and outward movement within the casing 36.

We provide two of these blocks and casings which are suspended from the main frame, near their forward ends, by standards 48. These members are mounted in parallelism and are so spaced that the spurs 40 of the chains 39 coöperate to form beet gripping and conveying members. By this construction we provide resilient gripping and holding means adapted to firmly hold the beets and convey them rearwardly of the machine a limited distance. Above each of the casings 36, and parallel therewith, we mount a casing 49. In this casing is secured a block 50 provided at each end with an approximately cylindrical recess 51. Sprocket wheels 52 and 52^a are mounted in these recesses and a sprocket chain 53 is passed around these wheels. This chain is provided with a plurality of equally spaced tapered V-shaped teeth 54. The sprocket wheel 52^a is keyed on the lower section 31^a of shaft 31. The chains 53 mounted in the casings 49 are thus driven, when the machine is in operation, so that the teeth 54 of the inner runs of the chains travel rearward of the machine thus forming a conveyer for the severed beet tops. A bevel gear 56 is keyed on a vertical shaft 55 and is in mesh with a bevel gear 57 formed integral with a spur gear 58 keyed on a stub shaft 59 supported by a U-bracket, or similar device, not shown, mounted on the side of the elevator casing 60. Above the casings 49 and parallel therewith we mount similar casings 66. These casings contain sprocket wheels and toothed chains similar to those mounted in the casings 49. The chains are driven by sprock-

ets which are keyed on the upper ends of the shafts 55. The two casings 49 and 66 are connected by a wall or board 67 secured between the same. In this manner the machine is provided with twin conveyer casings in which are housed an upper and a lower top conveyer spaced apart and supported by an intervening wall which narrows and limits the passage way between the twin casings so that when the beets are conveyed through the passage by the conveyer mechanism of the lower casing 36, the severed portions and leaves of the beets will be prevented from being caught or collected on or between the conveyer mechanism and casing. The lower casings 49 are extended forwardly and provided with integral outwardly turned points 68, the ends of which are bent into loops 69. The points and loops form an inwardly converging opening at the front of the passage between the two beet conveyers.

Below the points 68 of the casing 49 we mount two beet lifting members 70. Each of these members is of approximately circular cross section and is bent or turned outward toward the side of the frame. These members are carried by angle arms 71, the vertical shanks 72 of which are slidably mounted through vertical guide brackets 73 secured to the cross bar 7 of the main frame. These vertical arms have their inner edges toothed to form rack bars 72^a which mesh with quadrants 74 keyed on the shaft 75 rockably mounted in standards 76 secured to the cross bar 7. Near one end of the shaft 75 is keyed a hand lever 77. This lever is provided at its lower end with a slot 78 in which is mounted an arm 79 pivoted at one end in the slot. This arm is pivotally connected to the upper end of a detent 80 adapted to engage the teeth of a concave quadrant 81 secured to the cross bar 7 below the lever. A coil spring 82 is mounted in the recess in the lever adjacent the slot 78 and acts to normally hold the detent in extended position. The free end of arm 79 is secured to a pull rod 83, the upper end of which is secured to a latch lever in the usual manner. By rocking the shaft 75 by means of the lever 77 the lifting members 70 may be secured in any desired vertical adjustment.

The lifting members 70 may be quickly and easily adjusted vertically by means of the hand lever 77. By adjusting these members the height to which the beets will be lifted as the machine is drawn forward over a beet row may be accurately controlled so as to give direct and very accurate control of the distance to which the beet will project above the casings 36 carrying the beet holding and conveying means. As the topping means to be later described are mounted above and closely adjacent

these casings, it will be evident that adjustment of the lifters 70 provides means whereby the amount of the crown portion of the beet which is removed by the topping means 5 may be accurately controlled. This is of importance in harvesting beets which have been planted unevenly or where the size of the beets varies considerably, as will be understood. In addition, the main frame of 10 the machine is rigid and rigidly supports the casings 36 comparatively close to the ground surface so that but slight raising of the beets is necessary for the topping operation. This permits rigid mounting of the 15 casings holding the beet holding and conveying means thus insuring accuracy of operation of the topping apparatus as a whole.

The arms 71 carrying the lifting members 20 are braced by brace rods 84 pivotally secured thereto at their lower ends and passing through angularly disposed apertures through the front cross bar 6 of the main frame 1. These brace bars are provided 25 with heads 85 at their upper ends so as to positively limit the downward movement of the lifting members 70 and prevent withdrawal of the brace bars from the bar 6.

In back of the beet holders we mount an 30 upwardly and rearwardly inclined conveyer or elevator 60.

As will be noted from Figs. 1 and 3 of the drawings, the lifting members 70 are inclined upwardly and rearwardly. This inclination is such that, when in operative 35 position, the lifting members will lift the beet so as to bring the top of the crown flush with the under face of the lower top holder casings 49, as indicated by broken lines in 40 Fig. 1. As the beet leaves the upper ends of the members 70, it passes between the casings 36 containing the beet holding members. The beet is firmly gripped between the spurs 40 of the inner runs of the exposed chains 38 45 mounted on the resiliently supported blocks 35. The spurs hold the beet securely in an upright position and convey it toward the rear of the machine. As the beet travels rearwardly it encounters the rotating topping knives 108. These knives are secured 50 on the lower end of a rotatable shaft 109 on the upper end of which is keyed a fly wheel 110. The spur gear 111 is keyed on shaft 109 below the fly wheel 110. This gear 55 meshes with a spur gear 112 keyed on a vertical shaft 113 rotatably supported by a U-bracket or other suitable device, not shown, secured to the inner side face of the longitudinal brace bar 8. A bevel gear 114 is 60 keyed to the shaft 113 above gear 112 and meshes with a bevel gear 115 keyed on the inner end of the transverse counter shaft 15. By this means the knives 108 are rotated at a relatively high speed. As will be noted 65 from Figs. 2 and 3 of the drawings, the

topping knives project across the lower end of the passage between the top conveyers. As the beets are moved rearward by the spurs 40 the crowns and leaves are severed from the body of the beet by the knives 108. These 70 tops are conveyed rearward of the upper and lower top conveyers on to the elevator. In this connection it is to be noted that the lifting members 70 do not act as digging members but merely elevate the beets into 75 proper position to have the tops removed. This results in loosening the beets in the ground without actually digging or exposing them. Our invention is to be used as a 80 topper simply, and also as a means for loosening the beets without actually digging them. After topping, it is intended that the beets are to be dug and collected by a second machine of special construction.

At the back of the main frame we mount 85 a castering fork 116. This fork carries a short shaft 117 on the ends of which are loosely mounted the rear ground wheels 118. By providing this castering support for the back of the machine, and the pivotal connection 90 for the tongue frame 2 at the front of the machine, we insure that the machine will easily follow the surface of the ground upon which it is operated.

At the transverse center of the main frame 95 1, and near the front thereof, we provide a seat 119 of usual construction. This seat is supported by the usual inclined resilient standard 120, the lower end of which is secured to the front bar 6 of the frame. The 100 various operating hand and foot levers are so positioned relatively to the seat as to be readily accessible therefrom.

It will be obvious that there may be variations made in the construction and arrangement of the various parts of our invention 105 without departing from the field and scope of the same, and we intend to include all such variations as fall within the appended claims in this application, in which a preferred form only of the invention is disclosed.

What we claim, is:

1. The combination with the frame of a beet topping machine having beet lifting 115 members and topping mechanism suspended thereunder, of beet gripping and conveying members suspended from said frame and rigidly supported to lie beneath said topping mechanism and in close proximity to the 120 ground surface beneath said frame and with their receiving ends disposed closely adjacent the discharge end of said beet lifters, and a severed beet top conveyer disposed above said beet gripping conveyer and just 125 above the topping mechanism so that the latter is closely spaced to and shielded between said conveyers, said beet top conveyer projecting forwardly over and beyond the said beet lifters and curved outwardly and 130

downwardly to provide guiding means between the conveyers and toward the said shielded topping mechanism.

2. The combination with the main frame 5 of a beet harvester and beet lifting elements suspended thereunder, of a beet gripping, topping and severed beet-top conveyer mechanism associated therewith, said mechanism comprising a pair of spaced parallel 10 conveyer-casings having beet gripping and conveying means contained therein, supporting standards formed on each of said casings at one end thereof and projecting upwardly from one side for engagement to the 15 main frame whereby said casings may be positioned beneath said frame to lie in close proximity to the ground surface and with their receiving ends alining with and adjacent to the discharge end of the beet lifters, a twin conveyer casing mounted over 20 and above said first mentioned casing and in spaced relation thereto, said twin conveyer casing comprising an upper and lower housing having beet-top gripping and carrying 25 mechanism associated therewith, the said upper and lower housings being spaced from each other and supported in such spaced relation by an intervening wall embracing the said housings on the inner sides thereof 30 so as to provide a closed passage way between opposed twin conveyer casings, the lower casing of each of said twin casings

extending outwardly in curved formation from one end to project over and beyond the subjacent casing and the said beet lifters to 35 provide guide means for deflecting the beets into the passageway between each pair of spaced conveyer casings, a drive shaft disposed through each of the lower housings of the twin casings and the conveyer casing 40 subjacent thereto whereby the respective conveyer means of such members may be simultaneously actuated, the upper housing of each of said twin casings being provided with a separate conveyer drive shaft depending into the space between the upper and lower twin members and rearwardly of the walled passage, and a rotatable shaft extending through and beyond each of the 45 said twin casings and terminating at its 50 lowermost end in the space between the lower housing of the twin casing and the subjacent beet conveyer casing, and a topping knife affixed to said shaft at its lower end and projecting outwardly into the passage 55 way between the said opposed conveyer casings.

In testimony whereof we affix our signatures in presence of two witnesses.

WALTER L. JOHNSTON.
FRED L. JOHNSTON.
